UNITED STATES PATENT OFFICE.

EMIL BIEDERMANN AND ERNEST WILLIAM HARVEY, OF WESTMINSTER, ENGLAND, ASSIGNORS TO FREDERICK SIEMENS AND ALEXANDER SIEMENS, BOTH OF SAME PLACE.

METHOD OF UTILIZING PRODUCTS OF COMBUSTION.

SPECIFICATION forming part of Letters Patent No. 451,612, dated May 5, 1891.

Application filed September 27, 1890. Serial No. 366,349. (No model.) Patented in England November 18, 1884, No. 15,127.

To all whom it may concern:

Be it known that we, EMIL BIEDERMANN, a citizen of the Swiss Confederation, and ERNEST WILLIAM HARVEY, a subject of the Queen of Great Britain, both residing at 10 Queen Anne's Gate, Westminster, in the county of Middlesex, England, have invented a new and Improved Method and Means of Utilizing Waste or other Gaseous Products of Combustion, (for which we have obtained a patent in Great Britain, dated the 18th of November, 1884, No. 15,127,) of which the following is a specification.

Our invention relates to an improved method of utilizing the waste products of combustion from regenerative gas-furnaces of that class in which the air used to support combustion is heated prior to its admission into the combustion-chamber of the furnace.

Heretofore, so far as we are aware, the waste products of combustion from such furnaces have been impounded in regenerators, which in turn part with their heat to the gas and air supplied to the furnace. It has been proposed to utilize a portion of the gaseous products of combustion by causing such products to pass through incandescent fuel, so that the carbonic acid contained in the products of combustion may be converted into carbonic oxide, mingled with the other gases employed, and returned to the furnace to be burned in the usual manner.

Our invention consists, essentially, in utilizing one portion of the products of combustion for heating the air used in combustion and the other portion to aid in heating a mass of fuel, whereby the combustible gases contained in the fuel are set free and the carbonic-acid gas contained in the portion of the products of combustion transmitted through the incandescent mass of fuel will be transformed from carbonic acid or anhydride into combustible carbonic oxide. As is well known, the production of carbonic oxide is the result of the decomposition of the carbonic acid formed, in the first instance, above the grate by the incandescent carbon in the upper portion of the producer according to the equation $\text{CO}_2 + \text{C} = 2\text{CO}$. Carbonic acid at a high temperature is produced by the development of

heat in the lower layers of the fuel, which is transformed with the absorption of heat into carbonic oxide in traversing the red-hot fuel above, while hydrocarbons are distilled from the coal used and leave the producer with the carbonic oxide produced. In our improved process a portion of the products of combustion, together with such a quantity of air or oxygen as may be necessary to support combustion, is delivered under a mass of incandescent fuel, such as is usual in a gas-producer. The gases which are the product of combustion consist of carbonic acid, water in a gaseous state, and nitrogen, all in an intensely hot condition. In an ordinary gas-producer, if air or oxygen be admitted under a grate filled with incandescent coke, carbonic acid will be formed in the lower zone and produce a certain quantity of heat. This carbonic acid will be decomposed in the upper zone and absorb a portion of this heat. From this reaction it will be seen that the weight of carbon gasified in the lower zone is equal to that of the carbon gasified in the upper zone. Hence if we suppress the production of carbonic acid and replace it, as we do in our improved method, by the superheated carbonic acid of that portion of the products of combustion diverted through the fuel a saving of half of the fuel will be effected.

In the accompanying drawings, which illustrate our invention, similar letters of reference indicate like parts.

Figures 1 and 2 are longitudinal and transverse sections of a furnace provided with a retort-chamber. Figs. 3 and 4 are similar views illustrating a modification of such furnaces. Figs. 5, 6, and 7 are transverse sections through a furnace provided with a single producer and a pair of regenerators. Fig. 8 is a transverse section through a furnace provided with two gas-producers and two regenerators. Fig. 9 is a vertical section through a gas-producer of such a furnace. Fig. 10 is a transverse section through a furnace provided with suitable regenerators, and illustrates the position of a gas-duct between two producers. Fig. 11 is a vertical section through one of the producers on the line XX.

of Fig. 10. Fig. 12 is a transverse section through one of the gas-producers provided with an independent duct for drawing off the hydrocarbons.

- 5 The principle of operation is the same in all the figures. In Figs. 1, 2, 3, and 4 one portion of the products of combustion from the retort-chamber R is carried down the flues A and delivered under the mass of fuel in the producer F, the movement of the gases in the direction indicated being effected by the jet B, Figs. 1 and 2. The other portion of the products of combustion is transmitted through one or both of the regenerative chambers S.
- 10 In Figs. 5 and 6 the products of combustion are carried down the left-hand side of the figure to gas-producer F and regenerator S, and the converted gas and heated air carried back to the combustion-chamber through the flue A' and from the regenerator S'. This arrangement permits the reversal of the direction of the products of combustion, so as to permit of the heating of the regenerator.
- 15 In Fig. 6 reversing-valves V V' and W W' are shown, and the position of the jets B and B' is altered. The same is true of Fig. 7.
- 20 In Fig. 8 two fuel-chambers are shown on each side of the furnace. The products of combustion in this case descend by flue A and divide between the producer F and regenerator S. The gas passing through the producer F and regenerator S is carried by flue H to producer F', through producer F' to flue A', where it unites with the air from regenerator S' to be carried back to the furnace.
- 25 C and C' are small openings through which air or oxygen may be admitted to aid combustion, if required.
- 30 Fig. 10 shows a similar arrangement to Fig. 8, the gas-producers F F' in this case being divided by a longitudinal partition P. The direction of flow of the products of combustion is the same. The gas-flue H is located at the lower portion of the furnace, and the gas is transmitted upward through the producer F', instead of downward, as in Fig. 8.
- 35 In Fig. 12 a separate flue L is provided at the top of the producer, through which the hydrocarbons may be carried away separately from the gases derived from the products of combustion, which are carried downward through the mass of fuel and out by flue H.
- 40 55 We do not limit ourselves to any specific construction of furnace, as it is evident that

our improved method of utilizing the waste products of combustion may be employed in many different classes of furnace. In the several figures of the drawings we have shown 60 one portion of the products of combustion as transmitted through the fuel of the gas-producer. It is evident that the conversion of the carbonic acid of the spent gases into carbonic oxide may be effected in any mass of 65 fuel arranged independently of the gas-producer which generates the hydrocarbon gases combined with the converted gases for use in the combustion-chamber.

We claim as our invention—

1. The herein-described method of utilizing the waste products of combustion from a regenerative gas-furnace, which consists in extracting the heat from one portion of said products, thereby heating the air used in combustion and transmitting the remaining portion, together with air or oxygen, through a mass of fuel to heat it, generate carbonic oxide, and convert the carbonic acid of the spent gases so transmitted into carbonic oxide, and 80 burning the resultant gases in said furnace.

2. The herein-described method of utilizing the waste products of combustion from a regenerative gas-furnace, which consists in extracting the heat from one portion of said products, thereby heating the air used in combustion, and in transmitting the remaining portion, together with air or oxygen, through more than one independent mass of fuel to heat them, generate carbonic oxide, and convert the carbonic acid of the spent gases so transmitted into carbonic oxide, and finally 90 burning the resultant gases in said furnace.

In testimony whereof we have signed our names to this specification, in the presence of 95 two subscribing witnesses, this 8th day of July, A. D. 1890.
